CLAIM

The ornamental design for a bakery product, as shown and described.

DESCRIPTION

FIG. 1 is a front perspective view of a bakery product according to my design;

FIG. 2 is a left side perspective view thereof;

FIG. 3 is a top view thereof; and,

FIGS. 4-6 are views of the bakery product corresponding to FIGS. 1-3 after cooking.

The bottom of the bakery product is unornamented.
